CLAIM

The ornamental design for a decorative through-slot pattern for circular saw blade, as shown and described.

DESCRIPTION

FIG. 1 is a top plan view of a decorative through-slot pattern for circular saw blade in accordance with the invention disclosed and claimed herein, the bottom plan view being a mirror image thereof.

FIG. 2 is a top plan view of a second embodiment of a decorative through-slot pattern for circular saw blade in accordance with the invention disclosed and claimed herein, the bottom plan view being a mirror image thereof.

FIG. 3 is a top plan view of a third embodiment of a decorative through-slot pattern for circular saw blade in accordance with the invention disclosed and claimed herein, the bottom plan view being a mirror image thereof.

FIG. 4 is a top plan view of a fourth embodiment of a decorative through-slot pattern for circular saw blade in accordance with the invention disclosed and claimed herein, the bottom plan view being a mirror image thereof.

The broken line disclosure of a circular saw blade is for illustrative purposes and forms no part of the claimed design.
